UNITED STATES PATENT OFFICE.

FRANK M. LEAVITT, OF BROOKLYN, NEW YORK, ASSIGNOR TO EDWIN NORTON, OF MAYWOOD, AND OLIVER W. NORTON, OF CHICAGO, ILLINOIS.

CAN-HEADING MACHINE.

SPECIFICATION forming part of Letters Patent No. 390,086, dated September 25, 1888.

Application filed April 7, 1888. Serial No. 269,926. (No model.)

To all whom it may concern:

Be it known that I, FRANK M. LEAVITT, a citizen of the United States, residing in Brooklyn, in the county of Kings and State of New York, have invented a new and useful Improvement in Can-Heading Machines, of which the following is a specification.

My invention relates to machines for applying the heads or ends to the bodies of sheet-metal cans, and more particularly to certain improvements upon the can-heading machine shown and described in my pending application, Serial No. 247,873, filed August 25, 1887.

My present invention consists in the novel devices and novel combinations of parts and devices herein shown and described, and more particularly pointed out in the claims.

In the accompanying drawings, which form a part of this specification, and in which similar letters of reference indicate like parts, Figure 1 is a side elevation of a machine embodying my invention. Fig. 2 is a plan view. Fig. 3 is a detail section on line 3 3 of Fig. 1. Fig. 4 is a section on line 4 4 of Fig. 1. Fig. 5 is a section on line 5 5 of Fig. 1, and Fig. 6 is a vertical section on line 6 6 of Fig. 2.

In said drawings, A represents the frame of the machine, which may be of any suitable construction.

30 B is the can-body holding and sizing device, consisting, preferably, of two opening and closing semicircular rings or half-molds adapted to close upon the can body x or the end thereof, and hold, true up, and size the same, so that its outer periphery will correspond to the inner periphery of the can-head x' to be applied thereto by the piston C.

The two half rings or molds B B, which hold the can-body, are, as shown in the drawings, 40 mounted upon a movable carriage or slide, D, which reciprocates in suitable guideways, D', on the frame of the machine, and the half-molds are closed upon the can-body by means of stationary cams b b, against which the half-molds B B impinge as the slide D advances to bring the half-molds over the end of the can-body. The slide D is preferably hollow, and within it reciprocates the piston or device C, by which the can-heads are forced upon the 45 can-body.

The can-head-supply chute E, as well as the

can-body holder B, is mounted upon the slide or carriage D. This supply-chute is provided with one or more movable gates or guards, E', at its base, just in front of the piston C, to hold 55 the can-heads in position while the slide D is advancing and until the piston C moves forward in the slide D to force the can-head upon the can-body. The guard or guards E' are preferably operated by springs e through the 60 bent levers e', the levers being retracted at the proper moment as the slide D advances by impinging against the stop projections e' on the guide D'.

At the mouth of the half-molds B B is a 65 ring, b', which is of slightly larger diameter than the molds B when closed, so as to leave an annular recess or space at the mouth of the mold, equal to the thickness of the can-head flange, to receive said flange as the can-head is forced 70 upon the can-body. This ring b', in fact, constitutes part of the can-holder B as the end of the can-body projects into the same when the can-head is forced upon the can-body by the piston C; but this ring b' need not be made in 75 two parts, so as to have an opening and closing movement with the can-holder half-molds B, as the can-holder B and ring b' have an endwise movement on the slide or carriage D. It is therefore preferably made in the form of 80 a continuous or solid ring, and is rigidly attached to the slide D. The half-molds B may be opened by spring b'.

The piston C has a thick head, as shown in the drawings, so that as it moves forward under the can-head chute E to force one can-head upon a can-body the other can-heads in the chute will be supported by the piston-head itself. The slide D is reciprocated by cams D², which impinge against friction-rollers D³ on 90 the slide. The piston C is operated by a cam, C', which impinges against a friction-roller, C², on the piston. The piston C is retracted by a spring, C³. F is a support to bear against the opposite end of the can-body and resist the 95 thrust of the piston. All these parts and devices may preferably be constructed substantially the same as shown and described in my said former application, to which and to the patent to be granted thereon reference is hereby made for a more full description.

G is the can-body-supply chute, and H is an

intermittently-revolving can-body-feed wheel having receptacles h in its periphery adapted to receive a single can-body at a time from the chute G and deliver the same in position in front of the reciprocating can-body holder B , and then after the head has been applied to the can-body discharge the headed can into the discharge-chute G' . The discharge-chute G' is, in fact, but a continuation of the can-body delivery-chute G . The intermediate portion, g , of the chute G is made curved on a circle concentric with the can-body-feed wheel H , and serves as a guard to support and hold the can-bodies in the feed-wheel.

H' is a curved guard extending over the top of the feed-wheel. This guard is continued at $H' H^2$ to form the top wall of the supply-chute and discharge-chute. The feed-wheel H is given its intermittent motion by an ordinary Geneva stop-movement or mechanism, consisting of the slotted wheel h' on the shaft h^2 , to which the feed-wheel H is secured, and shaft h^3 , having mutilated disk h^4 and crank h^5 , furnished with pin or roller h^6 .

The cams which operate the slide D and piston C are secured on the driving-shaft K , which is furnished with a bevel-gear, k , that meshes with the bevel-gear k' on the counter-shaft k^2 , and the counter-shaft k^2 is furnished with a gear, k^3 , which meshes with a gear, k^4 , on the shaft h^3 of the Geneva stop-movement, through which the feed-wheel H is operated.

The machine shown in the drawings is specially adapted for putting on the final heads of filled cans; and for this reason the mechanism is mounted in an inclined position on the frame, and is provided with mechanism for applying only one head at a time. If it is desired to apply both heads simultaneously, the support F would be omitted and the mechanism duplicated at the other end.

I hereby disclaim, as not of my invention, the machines or devices shown and described in Patents Nos. 233,079, of October 12, 1880, to Dillon; 294,065, of February 26, 1884, to Norton and Hodgson, and 307,197, of October 28, 1884, to Jordan.

I claim—

1. In a can-body-heading machine, the combination, with a can-body holding and sizing device having radially opening and closing parts, of a reciprocating slide upon which it is mounted, an independently-moving piston or device for forcing the can-head upon the can-body, a can-body-supply chute, and a can-body feed device for automatically delivering

the can-bodies one by one into position in front of said bodily-reciprocating can-holder, and means for opening and closing the parts of said holder, substantially as specified. 60

2. The combination, with a bodily-reciprocating opening and closing can-holder, adapted to move endwise over the can-body and to close upon the same, of a piston reciprocating independently of said holder for applying the can-head, a can-body-supply chute, and an intermittently-revolving can-body-feed wheel, having pockets or receptacles to receive the cans one by one, substantially as specified. 65

3. The combination, with a can-body-supply chute, of an intermittently-revolving can-body-feed wheel above said chute, a device for holding the can-body, and a piston for applying the head thereto, said feed-wheel operating in conjunction with said chute to hold the can-body in position to be received by said can-body holder, substantially as specified. 70

4. The combination, with a bodily-reciprocating can-holder, of a can-body-supply chute, a can-body-feed wheel journaled above said chute and operating in conjunction therewith to hold the can-body in position to be received by said holder, and a piston reciprocating independently of said holder, substantially as specified. 75

5. The combination, with a can-body-supply chute, of a can-body-feed wheel, a bodily-reciprocating can-holder, a piston, and a can-head-supply chute, substantially as specified. 85

6. The combination, with a can-body-supply chute, of a can-body feed wheel, a bodily-reciprocating can-holder, a piston, a can-head-supply chute, and a movable guard for holding the can-heads in place at the base of said chute, substantially as specified. 90

7. The combination, with a bodily-reciprocating can-body holder adapted to move endwise over the end of the can-body and having two radially opening and closing parts, of a piston reciprocating independently of said holder for applying the head to the can-body while held in said holder, said can-body holder having a mouth portion, b' , large enough to receive the flange of the can-head outside of the can-body, a can-body-supply chute, and a can-body-feed wheel for delivering the can-bodies into position between said holder and piston, substantially as specified. 100
